UNITED STATES PATENT OFFICE.

ROSARIO GENOVESE, OF NEW YORK, N. Y., ASSIGNOR OF ONE-FOURTH TO HARRY SILVERMAN, ONE-FOURTH TO MORRIS STEINBERG, AND ONE-FOURTH TO PETER TASCANO, ALL OF NEW YORK, N. Y.

VENDING-MACHINE.

1,071,732.

Specification of Letters Patent.

Patented Sept. 2, 1913.

Application filed March 20, 1913. Serial No. 755,616.

To all whom it may concern:

Be it known that I, ROSARIO GENOVESE, a citizen of the United States, and residing at New York, in the county of New York and State of New York, have invented certain new and useful Improvements in Vending-Machines, of which the following is a specification, such as will enable those skilled in the art to which it appertains to make and use the same.

This invention relates to vending machines and particularly to machines of this class used for vending postage stamps; and the object thereof is to provide an improved machine of this class which is simple in construction, efficient in operation, and which, while being particularly designed for use in vending postage stamps, may also be employed for vending tickets, cards and like devices or articles.

The invention is fully disclosed in the following specification of which the accompanying drawings form a part, in which the separate parts of my invention are designated by suitable reference characters in each of the views, and in which;

Figure 1 is a plan view of my improved vending machine with the casing in which it is inclosed shown in section;—Fig. 2 a vertical section on the line 2—2 of Fig. 1;—Fig. 3 a vertical section on the line 3—3 of Fig. 1;—Fig. 4 a front view of the machine with the casing and part of the construction in section, and on the line 4—4 of Fig. 2;—Fig. 5 a vertical section on the line 5—5 of Fig. 1;—Fig. 6 a horizontal section on the line 6—6 of Fig. 2;—Fig. 7 a partial vertical section on the line 7—7 of Fig. 2;—Fig. 8 a partial section on the line 8—8 of Fig. 2;—Fig. 9 a partial section on the line 9—9 of Fig. 5, and;—Fig. 10 a partial section on the line 10—10 of Fig. 7.

My improved vending machine is placed in a box or casing *a* which is preferably rectangular in form and approximately square and which, in the form of construction shown, is provided with a bottom *a*² in which is placed a draw *a*³ provided with any suitable lock *a*⁴, and the draw *a*³, in the construction shown, is placed in any suitable box-shaped member *a*⁵ the top *a*⁶ of which

forms the bottom of the main box or casing on which the machine is placed and to which said machine is secured.

Mounted in the left hand portion of the box or casing is a main frame or support *b* provided with an open base *b*² within which is mounted a hopper *c* supported over and slightly in front of an opening *a*⁷ in the bottom *a*⁶ of the main box or casing and which communicates with the drawer *a*³, and the hopper *c* is provided with a base *c*² which ranges forwardly and backwardly of the machine, and beneath the hopper *c* and within the base *c*² is a slide *c*³ the rear end portion of which is provided with a longitudinal slot *c*⁴, and the base *c*² of the hopper *c* is provided with a bottom plate *c*⁵ over which the slide *c*³ moves, and countersunk in the top and central portion of the rear end of the plate *c*⁵ is a flat spring *c*⁶ provided with an upwardly curved rear end *c*⁷ having a longitudinal open slot *c*⁸.

The slide *c*³ is provided at its front end with a raised head *c*⁹ adapted to abut against the front wall *a*⁸ of the main box or case, and said slide is provided with a handle *d* which consists of a tube passed loosely through the front wall *a*⁸ of the main box or case and screwed onto the head *c*⁹ of the slide *c*³, and the handle tube *d* is provided with a head *d*² and operates as a plunger.

Mounted in the handle tube *d* is a spiral spring *d*³ the front end of which abuts against the head *d*², and the rear end of which abuts against a block *d*⁴ mounted in the rear end portion of the handle tube *d* and provided with vertical pins *d*⁵ which pass through corresponding longitudinal slots *d*⁶ in the top and bottom or opposite sides of the handle tube, and the pins *d*⁵ bear on the front wall *a*⁸ of the main box or case, and in order to move the slide *c*³ inwardly, all that is necessary is to force the handle tube *d* inwardly and when the pressure applied thereto is removed, the spring *d*³ will force the handle tube and the slide *c*³ outwardly into their outermost positions, as shown in Figs. 2 and 6.

The main frame or support *b* consists of parallel vertical members *b*³ with which is connected a supplemental back frame or sup-

port e consisting of parts e^2 , e^3 , e^4 , and e^5 secured together and to the main frame or support, and said main frame or support is also provided with a horizontal extension f consisting of parallel plates f^2 which extend to the right of said main frame or support, all of which is clearly shown in Figs. 1, 2, 3, 4 and 5.

Mounted below the extension f of the main frame or support in standards f^3 is a roller f^4 on which, in practice, the stamps to be vended are wound, said stamps being connected in a continuous strip f^5 which is perforated transversely, in practice, to separate the successive stamps and to form transverse rows between the successive stamps whereby they may be easily detached, but these perforations of the strip are not necessary.

In the right hand end portion of the extension f of the main frame is mounted a tension device f^6 preferably consisting of a helical spring the free end f^7 of which bears on the roller f^4 to prevent the too free unwinding therefrom of the stamps. Mounted centrally of the extension f of the main frame is a large guide roller f^8 over which the strip f^5 of stamps is passed, and this guide roller is provided with a cushioned surface f^9 preferably composed of rubber, but which may be composed of fibrous material.

A large main feed roller g is mounted in the main frame or support b and in the same horizontal plane as the guide roller f^8 , and the feed roller g is also preferably provided with a cushioned surface g^2 , and with side flanges g^3 , and between the main feed roller g and the guide roller f^8 is placed a smaller guide roller g^4 also preferably provided with a cushioned surface of rubber or similar material, and the strip f^5 of stamps is passed over the guide roller f^8 beneath the roller g^4 and over the main feed roller g , and mounted directly over the main feed roller g is a supplemental and smaller feed roller g^5 which bears on the roller g or on the strip of stamps f^5 as it passes over said feed roller g , and the roller g^5 is also preferably provided with a cushioned surface g^6 .

At the left of the main frame or support b is a plate standard h having a foot piece h^2 secured to the bottom a^6 of the main box or case, and the plate standard h is provided with a transverse head h^4 to the outer side of which is secured a transverse stationary blade h^5 , and to the inner side of which is secured an angle piece h^6 provided with a horizontal chute h^7 through which the stamps or strip of stamps passes, and the chute h^7 is provided with a projecting base tongue piece h^8 which reaches, approximately, the surface of the main feed roller g , and said chute is also provided with a top spring tongue h^9 which also reaches or touches the surface of the main feed

roller g , and in the operation of the machine the stamps, or the strip f^5 of stamps, passes between the tongues h^8 and h^9 and through the chute h^7 which extends through the plate standard h , as clearly shown in Fig. 3.

The stationary blade h^5 and the angle piece h^6 provided with the chute h^7 are both secured to the plate standard h by a pin or bolt h^{10} , and a spring tongue h^{11} is also secured to the plate standard h by the pin or bolt h^{10} and, extends to the left of said plate standard, and the end of the spring tongue h^{11} is in the same plane as the end of the chute h^7 and when a stamp is projected from the chute, as shown at f^{10} in Fig. 3, it is held in a horizontal position until cut off or detached from the strip f^5 , as hereinafter described, and the said stamp when cut off falls into a delivery chute i which is shown in full lines in Figs. 1, 3 and 4, and in dotted lines in Fig. 5.

The chute i may be connected with the standard plate h in any desired manner and extends downwardly and forwardly and communicates with a transverse slot or opening i^2 in the front wall a^8 of the main box or casing, and each time that a stamp is detached it passes down through said chute and out at the front of said box or casing.

The inner top side portion of the chute i adjacent to the chute h^7 is open, as shown at i^3 , and the opposite side is also open, as shown at i^4 , and the main box or case is provided with a transparent panel i^5 through which the above described operation of projecting a stamp and cutting it off may be seen.

A movable blade j is pivoted to the cross head h^4 of the plate standard h , or to the stationary blade h^5 , as shown at j^2 , and said movable blade ranges backwardly and is provided at its rear end with a pin j^3 which extends to the right and is movable in a vertical slot j^4 in a link j^5 pivoted at its lower end and as shown at j^6 , to a lever j^7 which is pivoted in the rear of the main box or case at j^8 , and the lever j^7 extends through a vertical slot j^9 in the front wall of the main box or case and is provided with a handle j^{10} , and a spring j^{11} is placed beneath the inner end portion of the lever j^7 and normally holds it in a raised position as shown in Fig. 5, and said lever is provided with a pin or screw j^{12} movable in a curved slot j^{13} in the plate standard h and which serve to limit the upward and downward movement of said lever.

The pin j^3 extends inwardly in the direction of the main frame or support and a spring k is secured to the transverse head h^4 of the plate standard h , as shown at k^2 , and extends backwardly and beneath the pin j^3 and the end thereof is curved upwardly, as shown at k^3 , and said spring serves to hold the blade j in its raised position.

5 Mounted transversely in the back supplemental frame e is a shaft k^4 through the outer end of which is passed a pin k^5 which ranges forwardly and backwardly and a link k^6 is suspended from the pin j^3 , and the lower end of said link is pivoted at k^7 to the forward end of the pin k^5 . The link k^6 is provided with a slot k^8 through which the pin j^3 passes and in the head of said link is 10 a set screw k^9 to limit the movement of the pin j^3 in the slot k^8 , or regulate the extent of said movement.

15 The inner end of the shaft k^4 is provided with a spring hammer arm m having a head m^2 which operates as a hammer on a gong m^3 secured to the back member of the main frame extensions f^2 , and at each operation of the machine, in cutting off a stamp, the hammer m^2 strikes the gong m^3 .

20 The main feed roller g is mounted on a shaft m^4 and the supplemental feed roller g^5 is mounted on a shaft m^5 , and the rear end of the shaft m^4 is provided with a wheel n the hub of which is provided with ratchet 25 teeth n^2 five of which are shown, and said hub is also provided with radial arms n^3 which are also five in number, as clearly shown in Fig. 8, and the ends of the arms n^3 are provided with semi-circular recesses 30 n^4 . Pivoted at o in the supplemental frame e below the wheel n is an arm o^2 the head of which is provided with an upwardly directed nose o^3 which operates in the recesses n^4 in the arms n^3 of the wheel n , and the 35 head of said arm is also provided with a backwardly directed finger o^4 to which is pivoted a dog o^5 .

Pivoted in the back supplemental frame member e at o^6 is a dog p the head of which 40 is provided in its front edge with a circular recess p^2 , and the dog o^5 is provided with a nose o^7 which operates in the recess p^2 . The dog o^5 is mounted on a pivot pin o^8 on which is also mounted a dog r having a nose 45 r^2 which operates in connection with the ratchet teeth n^2 on the hub of the wheel n , and the dog r is provided with a spring r^3 which operates on the dog o^5 , and the nose r^2 of the dog r operates through a slot e^6 in 50 the inner side of a casing e^7 which forms a part of the back supplemental frame e and in which the dog p is mounted.

A spring s is mounted rearwardly of the dog p and operates in connection therewith 55 to force said dog forwardly or into the position shown in Fig. 2, and this forward movement of said dog is limited by the nose p^3 thereof striking the part e^2 of the supplemental frame e .

60 The lower end of the arm o^2 is provided with a finger o^9 which operates in the slot e^8 in the rear end of the spring e^6 , and said finger also operates in a groove o^{10} in the top portion of the bottom plate e^5 of the base 65 e^2 of the hopper e .

A tension spring s^2 is connected with the arm o^2 centrally thereof and with the main frame or support at s^3 , and serves to hold said arm in the position shown in Fig. 2.

70 The shaft m^4 of the main feed roller g is provided at its front end with a large gear s^4 , and the shaft m^5 of the supplemental feed roller g^5 is provided at its front end with a smaller gear s^5 which meshes therewith and the supplemental guide roller g^4 75 is provided with a gear s^6 which meshes with the gear s^4 .

The spring f^6 is connected with a sleeve s^7 through which is passed a shaft s^8 which is provided with a forward extension on 80 which is mounted a reel s^9 .

The shaft m^4 of the main feed roller g is projected forwardly and provided with a feed wheel t . The shaft t^2 of the guide roller f^8 is projected forwardly and provided with a tape reel or casing t^3 of the spring drum type, and the shaft t^4 of the guide roller g^4 is also projected forwardly and provided with a sleeve bearing t^5 , and supported directly over the front end of the 90 shaft t^4 and sleeve bearing t^5 is another sleeve bearing t^6 . The main feed roller g is keyed to its shaft as is also the supplemental feed roller g^5 , and the rollers f^8 and g^4 are loosely mounted on the corresponding 95 shafts t^2 and t^4 .

Wound in the spring tape reel or casing t^3 is an ordinary measuring tape u which serves as a counting tape and is provided with a scale of inches and fractions thereof 100 and also provided, at regular intervals representing a quarter of an inch, with holes u^2 , and the feed wheel t on the front end of the shaft m^4 is provided with corresponding sprockets or pins u^3 which pass through the 105 holes u^2 in the tape u , and said sprockets or pins are also five in number, in the construction shown.

In the use of the machine the tape u is drawn out of the tape reel or casing t^3 and 110 is passed over the sleeve bearing t^5 beneath and around the feed wheel t , back over the sleeve bearing t^6 and then back to and connected with the reel s^9 . The reel s^9 is provided with a milled hub v by which it may 115 be turned and which serves as a handle for this purpose, and a friction spring v^2 mounted inwardly of said reel prevents the too free turning thereof in the operation of the machine, as hereinafter described.

120 The feed wheel t is loosely mounted on the shaft m^4 and mounted on the front end portion of said shaft is a threaded thumb and finger nut v^3 having a flange v^4 adapted to bear on the hub of the wheel t so as to press said wheel t in connection with the hub of the gear s^4 , as shown in Fig. 2, and compel the wheel t to turn with the said gear and the shaft m^4 on which it is mounted.

125 In the front portion of the machine is a 130

coin chute w which extends from the top front portion of the box or case a downwardly and backwardly and discharges into the hopper c , and said coin chute communicates with a coin slot w^2 in the top of the main box or case a .

In beginning the operation of the machine, the tape u is first mounted, as shown in Fig. 4, and as hereinbefore described, and the feed wheel t loosened or released by turning the thumb nut v^3 and the tape is fully wound on the reel, s^9 until the first of the holes n^2 , which will be indicated by an inch mark on the tape u , bears centrally above the shaft t^4 , after which the feed wheel t is tightened on the shaft m^4 by turning the thumb nut v^3 . It is also necessary to adjust the strip of stamps f^5 so that the end thereof which is to be fed through the machine between the feed rollers g and g^5 will register with one of a number of marks on the feed roller g . These marks may be placed on the face of the feed roller g , or on the flange or flanges g^3 thereof and will be five in number, and in Fig. 3 of the accompanying drawings, I have shown these marks on one of the flanges g^3 at y . After adjusting the strip f^5 of stamps, as described, the rollers g and g^5 are turned so as to feed the end of the strip f^5 between said rollers until the edge thereof is flush or even with the end of the tongue h^8 of the chute h^7 at y^2 . The adjuster of the machine then drops a coin into the chute w and forces the plunger handle d inwardly and the mechanism of the machine is operated to drop the said coin into the draw a^3 and to project the end of the stamp strip through the chute h^7 so that the front edge of the end stamp will be even with the edge of the stationary blade h^5 . The machine is now in condition for use, and by the insertion of a coin through the slot w^2 and the operation of the plunger handle d , as hereinbefore described, a stamp will be projected into the delivery chute i , as shown at f^{10} , and cut off and dropped in said chute and delivered at the front of the box or case, and at the same time the tape u will be turned one step, and it will also be understood that by means of this tape the number of stamps vended at any particular time may be determined as may also the number still remaining in the strip wound on the roller f^4 .

In the operation of the machine, a party desiring a stamp drops a coin through the slot w^2 into the chute w , and said coin passes down into the hopper c and falls onto the plate c^5 , as shown at x , in Fig. 2 and Fig. 6.

The handle tube d which operates as a plunger is then forced backwardly and this operation moves the slide c^3 backwardly and said slide forces the coin x backwardly, as shown in dotted lines at x^2 in Fig. 6, until it strikes the finger o^9 of the arm o^2 , in

which operation the coin passes over the spring c^6 and depresses said spring c^6 and the backward movement of the slide c^3 and coin x continues until said coin reaches the position shown at x^3 in Fig. 6, and the arm o^2 reaches the limit of its backward movement, in which position of said arm the finger o^9 extends downwardly back of the coin at x^3 , as indicated in dotted lines at x^4 in said figure. It will be understood that the slot c^4 in the slide c^3 is to enable said slide to clear the spring c^6 in the above described operation, and during the backward movement of the arm o^2 and the coin x , as above described, the nose p^3 of the dog p is forced backwardly by the dog o^5 against the operation of the spring s , and at the same time the wheel n and the shaft m^4 are turned one step by the dog r the nose of which engages one of the ratchet teeth n^2 on the hub of the wheel n , this operation being due to the spring r^3 of the said dog r which engages the dog o^5 and the movement of the wheel n is limited by the nose o^3 of the arm o^2 entering the recesses n^4 in the end of one of the arms n^3 of said wheel.

The above described operation of the shaft m^4 turns the feed wheel t of the tape u one step, and said tape is moved one step and is rewound to this extent in the spring drum or reel t^3 . In this operation, as will be understood, the strip f^5 of stamps is fed one step, or the length of one stamp, forwardly between the feed rollers g and g^5 , and the first stamp passes through the chute h^7 and is projected, as shown at f^{10} in Fig. 3, and at this time the blade j is depressed by the forward movement of the dog p due to the operation of the spring s into the position shown in Fig. 2, which operation depresses the link k^6 due to the rotation of the shaft h^4 and the pin h^5 connected therewith and with said link.

From the foregoing description it will be seen that the blade j is operated together with the rest of the mechanism of the machine by the inward movement of the handle tube or plunger d , but I also provide means for operating the blade j independent of the other mechanism of the machine, and this means consists of the lever j^7 and the link j^5 connected with said blade, as shown and as hereinbefore described, and, if, at any time, a stamp should not be fully severed by the first downward and automatic movement of the blade j , said blade may be operated by means of the lever j^7 which can be depressed by hand, as will be readily understood, for the purpose of cutting off or severing a stamp from the strip f^5 , and a stamp so cut off will pass downwardly through said chute i and out through the slot or opening i^2 in the front of the casing or machine.

From the foregoing description it will also be apparent that each time that a coin is

dropped into the chute *w* and the plunger handle *d* forced backwardly, the machine will be operated as herein described, and a stamp will be projected into the delivery chute *i* and cut off and be delivered at the front of the machine, and while I have described my machine as preferably for use in vending stamps, it will be apparent that my invention is not limited to this use, as the machine may be used for vending tickets or cards of any kind or class arranged in strips, and said tickets or cards, as well as stamps, may be of any size and the stamps may be of any denomination, it being understood that the coin chute *w* and slide mechanism at the bottom of the hopper *c* may be regulated to any desired extent to correspond with coins of any dimensions, and it will also be understood that the tape *u* and the spaces between the holes *u*² may be regulated as may be desired, as may also the feed wheel *t* and the pins *u*³ connected therewith, and the construction and arrangement of the machine, as a whole, may therefore be such as to vend stamps, tickets or cards arranged in strips and of any dimensions, and various changes in and modifications of the form, construction and operation of various parts of the operative mechanism of my improved machine may be made, within the scope of the appended claims, without departing from the spirit of my invention or sacrificing its advantages.

From the foregoing description it will also be seen that each quarter inch movement of the tape *u* and each quarter inch movement of the feed wheel *t* results in the projection of one stamp through the chute *h*⁷, or the projection of the strip *j*⁵ through said chute to the extent of the length of one stamp, and the wheel *n* being provided with five arms *n*³, it will be seen that the main feed wheel *g* is moved one-fifth of a revolution at each operation of the machine, and the circumference of this wheel, therefore, must be just five times the length of a stamp, or equal to the length of five stamps.

After the backward movement of the slide *c*³ and the movement of the coin *x* over the spring *c*⁶ into the position shown at *x*³, as hereinbefore described, and the depression of said spring in this operation, the said spring rises into the position shown in Fig. 2, and in the forward movement of the arm *o*² the finger *o*⁹ thereof forces the coin forwardly, and in this movement the said coin passes under the raised end of the spring *c*⁶ and falls through the aperture *a*⁷ into the draw *a*³ and at the end of this movement the parts of the machine are in position to be again operated by the insertion of a coin into the chute *w* and the backward movement of the handle tube or plunger *d*, due to the action of the spring *s*².

Having fully described my invention,

what I claim as new and desire to secure by Letters Patent, is:—

1. In a machine for vending stamps, tickets and the like arranged in flexible strips, a casing, a frame mounted therein, a delivery chute supported in connection with said frame, a strip feed chute adjacent to and communicating with the delivery chute, a main feed roller mounted adjacent to the strip feed chute and forming a part of a series of rollers adapted to support a flexible strip, a pivoted operating arm, a wheel mounted on one end of the shaft of the main feed roller and provided with radial arms which operate in connection with the pivoted operating arm and on one side thereof with a ratchet, a main spring controlled dog, a supplemental spring controlled dog operated by said arm and engaging said ratchet, another supplemental spring controlled dog operated by said arm and engaging the main spring controlled dog, whereby, at each operation of said arm said strip will be projected through the strip feed chute one step, and a blade also operated by said arm for cutting off a part of said strip at each movement of said arm.

2. In a machine for vending stamps, tickets or the like, arranged in flexible strips, a casing, a frame mounted therein, a delivery chute supported in connection with said frame, a strip feed chute adjacent to and communicating with the delivery chute, a main feed roller mounted adjacent to the strip feed chute and forming a part of a series of rollers adapted to support a flexible strip, a pivoted operating arm, a wheel mounted on one end of the shaft of the main feed roller and provided with radial arms which operate in connection with the pivoted operating arm and on one side thereof with a ratchet, devices operated by said arm and adapted to engage said ratchet and turn the main feed roller one step at each operation of said arm, and a pivoted blade operated by said arm for cutting a stamp from the end of said strip at each movement of said roller.

3. In a machine for vending stamps, tickets or the like, arranged in flexible strips, a casing, a frame mounted therein, a delivery chute supported in connection with said frame, a strip feed chute adjacent to and communicating with the delivery chute, a main feed roller mounted adjacent to the strip feed chute and forming a part of a series of rollers adapted to support a flexible strip, a pivoted operating arm, a wheel mounted on one end of the shaft of the main feed roller and provided with radial arms which operate in connection with the pivoted operating arm and on one side thereof with a ratchet, devices operated by said arm and adapted to engage said ratchet and turn the main feed roller one step at each opera-

tion of said arm, a pivoted blade operated by said arm for cutting a stamp from the end of said strip at each movement of said roller, and hand operated devices also connected with said blade and adapted to operate it.

In testimony that I claim the foregoing as

my invention I have signed my name in presence of the subscribing witnesses this 17th day of March, 1913.

ROSARIO GENOVESE.
